UNITED STATES PATENT OFFICE.

CHARLES SZALAI, OF EASTON, PENNSYLVANIA.

WINDOW LOCK.

Application filed March 23, 1922. Serial No. 546,051.

To all whom it may concern:

Be it known that I, CHARLES SZALAI, a citizen of Hungary, residing at Easton, in the county of Northampton and State of Pennsylvania, have invented certain new and useful Improvements in Window Locks, of which the following is a specification.

This invention relates to certain new and useful improvements in window locks and 10 has particular reference to a locking device carried by the upper rail of the lower sash that is adapted for engagement with the lower rail of the upper sash to retain the window frame in a locked position, and is 15 further adapted for engagement with the side rails of the upper sash at different points, to hold the windows in a locked partly opened position.

With the above general objects in view 20 the invention consists of the novel combination and arrangement of parts hereinafter more fully described in connection with accompanying drawing, and in which like reference characters designate corresponding parts throughout the several views.

In the drawings:—

Fig. 1 is a fragmentary side elevational view of a portion of a window casing and frame showing the window lock carried by 30 the upper rail of the lower sash and spaced sockets carried by a side rail of the upper sash,

Figure 2 is a vertical sectional view taken on the line II—II of Fig. 1,

Fig. 3 is a side elevational view of the lock removed from the window sash showing the locking bolt in its projected position,

Fig. 4 is a longitudinal sectional view taken on line IV—IV of Figure 3 showing 40 the side grooves in the upper side of the locking bolt,

Fig. 5 is a longitudinal sectional view of the lock showing the tensioned pin carried by the lock casing extending into the groove 45 of the locking bolt, and also showing the groove in the bolt casing for guiding the locking lug carried by the bolt,

Fig. 6 is a detail sectional view taken on line VI—VI of Fig. 3 showing the locking 50 lug carried by the bolt and the side notches in the bolt casing for receiving the same,

Fig. 7 is a detail sectional view taken on line VII—VII of Fig. 3 showing the bolt groove in its uppermost position,

55 Fig. 8 is a detail cross sectional view show-

ing the locking bolt partially rotated and the pin removed from the bolt groove,

Fig. 9 shows side and front elevational views of the keeper socket for the lock bolt, and

Fig. 10 is a front elevational view of a modified form of spaced plate for the keeper sockets.

Referring more in detail to the accompanying drawing, there is illustrated the 65 window frame 1 having coacting lower and upper sashes 2 and 3, the lower sash being provided with a top rail 4 while the upper sash carries a lower rail 5 and a side rail 6. The lock associated with the window is carried by the upper rail of the lower sash, the lock embodying the barrel 7 having a face plate 8 countersunk within the upper rail 70 of the lower sash as shown in Figures 1 and 2, the barrel being provided with a longitudinally extending axial bore 9 which communicates with a longitudinally extending side opening groove 10 in the ends of the barrel as shown in Figure 5, and a side opening 75 11 in the barrel 7 diametrically opposite the groove 10 adjacent the outer end of the barrel.

A sliding bolt 12 is freely movable within the barrel bore 9 having upon the outer end thereof an operating knob 13. A block 14 85 is carried by the bolt 12 and is freely slideable in the groove 10, the inner end of the groove communicating with side sockets 15, into which the block 14 may be selectively positioned upon rotation of the bolt to hold 90 the bolt in position against movement relative to the barrel casing 7.

To maintain the block 14 in position aligned with the groove 10, the upper side of the bolt 12 is provided with a longitudinally extending groove 16 into which a finger 17 located within the opening 11 formed in the barrel 7 is received, the finger 17 being spring pressed as at 18 with the spring confined in the opening 11 by the screw 100 plug 19.

The socketed keeper member for the projecting end of the lock bolt 12 is shown in detail in Figure 9, the same embodying a face plate 20 comprising a tubular extension 105 21 that is countersunk within the lower rail 5 of the upper sash and also disposed in spaced vertical positions upon the side rails 6 of the upper sash as shown in Figures 1 and 2, the socketed keeper member being 110

retained in position by fastening devices extending through openings 22 in the face plate 20 of the keeper, while the face plate and tubular extension 21 has a central bore 23 for the reception of said bolt. A modified form of keeper is shown in Figure 10 and embodies a rectangular plate 24 having openings 22 by which the same may be secured to the lower rail of the upper sash, 10 and also to the side rail thereof, the plate 24 being provided with a central opening 25 registering with a socket in the rails of the upper sash.

From the above detailed description of the device, it is believed that the construction and operation thereof will at once be apparent, it being noted that the spring pressed finger 17 is positioned in the groove 16 of the locking bolt 12, the block 14 carried by said bolt registers with the groove 10 so that the bolt 12 may be shifted axially of the barrel 7 by gripping the knob 13. When it is desired to lock the bolt 12 in its extended position as shown in Figure 5, the bolt 12 is rotated in either direction by the knob 13 to displace the spring pressed finger 17 from engagement in the groove 16, the bolt and spring pressed fingers occupying the relative positions shown in Figure 8, while the block 14 is received in either of the sockets 15 as shown by dotted lines in Figure 6, the bolt when so positioned being prevented from longitudinally shifting movement within the casing barrel 7. The bolt 35 when locked in its extended position is received in the socketed keeper with the two window sashes 2 and 3 locked in a closed position, or locked in a partially open position. Should it be desired to eliminate the tubular extension 21 from the keeper plate 20, the type of keeper plate 24 as shown in Figure 4 may be employed and is secured to the lower rail 5 of the upper sash and also to the side rails 6 thereof. When restoring the bolt 12 to a position to permit sliding movement thereof, the same is rotated and it can be readily determined when the spring pressed finger 17 is received in the bolt groove 16 with the block 14 again

aligned with the groove 10 whereupon sliding movement of the bolt 12 within the barrel casing 7 is permitted.

While there is herein shown and described the preferred embodiments of my invention, it is to be understood that minor changes in the construction, combination and arrangement of parts may be made without departing from the spirit and scope of the invention.

Having thus described the invention, what I claim as new is:

1. A window lock of the type described comprising a barrel casing having an axial bore therein, said casing having a longitudinally extending groove opening at one side thereof and communicating with the axial bore and laterally positioned sockets in the barrel communicating with said groove and bore at one end of said groove, a bolt slidably mounted in said bore, a block carried by the bolt adapted for sliding movement in the barrel groove and for selective positioning in either of said sockets, said barrel comprising a spring pressed finger extending into the bore, and said bolt having a longitudinal groove therein to receive said finger.

2. A window lock of the type described comprising a casing having an axial bore and a side opening groove communicating with the bore with lateral sockets formed at one end of the groove, a bolt slidably mounted in the bore of the casing, a block projecting laterally from said bolt into said groove, said bolt having a longitudinal groove therein, said casing having a side opening communicating with the casing bore, a spring pressed finger positioned in said opening and extended into the bolt groove for determining the relative positions of the bolt carried block and the groove in the lock casing.

In testimony whereof I affix my signature.

CHARLES SZALAI.
